UNITED STATES PATENT OFFICE.

ALEXANDER DEAK AND JOSEPH DEAK, OF BROOKLYN, NEW YORK.

AERIAL VESSEL.

1,327,529.

Specification of Letters Patent.

Patented Jan. 6, 1920.

Application filed May 3, 1918. Serial No. 232,372.

To all whom it may concern:

Be it known that we, ALEXANDER DEAK and JOSEPH DEAK, both citizens of the United States, and residents of the city of New York, borough of Brooklyn, in the county of Kings and State of New York, have invented a new and Improved Aerial Vessel, of which the following is a full, clear, and exact description.

10 The invention relates to aeroplanes and similar aerial vessels, and its object is to provide certain new and useful improvements in aerial vessels whereby sudden dropping, in case the motor stops, is entirely prevented, and the pilot is enabled to safely guide the aerial vessel to a suitable landing. Another object is to prevent the aerial vessel from capsizing in case the motor stops. Another object is to balance 15 the aerial vessel in case of a rapid descent.

With these and other objects in view, the invention consists of certain novel features of construction as hereinafter shown and described and then specifically 20 pointed out in the claims.

A practical embodiment of the invention is represented in the accompanying drawings forming a part of this specification in which similar characters of reference indicate 25 corresponding parts in all the views.

Figure 1 is a side elevation of the improved aeroplane, parts being shown in section;

Fig. 2 is a plan view of the same; and 30 Fig. 3 is a side elevation of a modified form of the aeroplane with the sustaining planes in vertical position.

In the body 10 of the aeroplane is mounted the usual motor 11 having a motor shaft 40 12 adapted to be connected by a clutch member 13 with a clutch member 14 secured on a propeller shaft 15 carrying the usual driving propeller 16 disposed at the front end of the body 10. The aeroplane shown in

45 Figs. 1 and 2 is provided with upper and lower sustaining planes 20 and 21, of which the upper sustaining plane on each side of the body 10 is made in two sections or parts 22 and 23 attached to shafts 24, 25

50 journaled in suitable standards 26, 27 mounted on or forming part of the body 10. The lower sustaining plane 21 on each side of the body 10 is likewise made in two sections or parts 30 and 31 attached to shafts 32, 33 journaled in standards 34, 35 attached to or forming part of the body 10.

Normally the inner ends of the sections 22, 23 and those of the sections 30 and 31 meet to form an approximately horizontal sustaining plane, but the said sections may 60 be swung into an approximately vertical position, as indicated in dotted lines in Fig. 1, to prevent the aeroplane from capsizing in case the motor stops and to balance the aeroplane in case of a rapid descent. 65 The sections 22, 23 and 30, 31 are under the control of the pilot of the aeroplane, and for this purpose the shafts 24, 32 and 25, 33 are provided with pulleys 40, 41 connected by belts 42, 43 with pulleys 44, 45 secured 70 on a shaft 46 journaled on the body 10 and provided with a lever 47 within reach and under the control of the pilot to permit the latter to swing the sustaining plane sections 22, 23, 30, 31 from normal horizontal 75 position into vertical position for the purpose previously explained.

A distance above the upper sustaining plane 20 is arranged a horizontally disposed safety propeller having its vertical shaft 51 80 journaled in suitable bearings arranged on the body 10. The axis of the safety propeller 50 is approximately at the center of gravity of the aeroplane, and this propeller is provided with more than two wings, pref- 85 erably four wings, for instance, as shown in Figs. 1 and 2. In case the motor 11 stops and the propeller wheel 16 ceases to rotate and the aeroplane begins to drop then the safety propeller 50 begins to rotate thus 90 tending to sustain the aeroplane in the air or, at least, to check its rapid descent to permit the making of a safe landing.

In order to facilitate the making of a safe landing the rotary motion of the safety propeller 50 is transmitted to the driving propeller 16, and for this purpose the following arrangement is made: For the purpose mentioned, the shaft 51 is provided with a bevel gear wheel 60 in mesh with a bevel gear wheel 61 provided with a sprocket wheel 62 connected by a sprocket chain 63 with a sprocket wheel 64 secured on a shaft 65 arranged within the body 10. On the shaft 65 is secured a clutch member 66 adapted to engage a clutch member 67 loose on the shaft 65 and provided with a sprocket wheel 68 connected by a sprocket chain 69 with a sprocket wheel 70 attached to or forming part of the clutch member 14 loose on the shaft 110 15. The clutch member 13 is normally in engagement with the clutch member 14 and

is mounted to turn with and to slide on the motor shaft 12, and the clutch member 66 is likewise mounted to turn with and to slide on the shaft 65 while the clutch member 67 is loose on the said shaft. The clutch members 13 and 66 are engaged by shifting forks 80 and 81 attached to a shaft 82 provided with a handle 83 connected by a link 84 with a lever 85 within reach and under the control of the pilot. Thus by the pilot manipulating the lever 85 a rocking motion can be given to the shaft 82 which by the shifting forks 80 and 81 throws the clutch member 13 out of engagement with the clutch member 14 and throws the clutch member 66 into engagement with the clutch member 67 so that the motor shaft 12 of the motor 11 is disconnected from the propeller shaft 15 while the latter is connected with the shafts 65 and 51 by the connection described to cause the rotation of the safety propeller 50 to be transmitted to the driving propeller 16. From the foregoing it will be seen that by the arrangement described the pilot can readily connect the safety propeller 50 with the driving propeller 16 at the time the motor 11 comes to a stop to drive the propeller 16 from the propeller 50 which latter is caused to rotate owing to the dropping of the aeroplane after the motor stops. It will be noticed that when both propellers 50 and 16 rotate in unison the aeroplane is not liable to drop straight down but glides down along an inclined path to insure a safe landing. When the motor 11 comes to a stop through accident or otherwise, the pilot can swing the sections 22, 23, 30 and 31 of the sustaining planes 20 and 21 into vertical positions thus preventing the aeroplane from capsizing and maintaining the aeroplane in the proper balance to insure a safe landing.

Instead of making each sustaining plane 20 and 21 in sections, the top sustaining planes 100 and 101 on opposite sides of the body 102 of the aeroplane shown in Fig. 3 are mounted to swing from normal horizontal position into approximately vertical position, and the lower sustaining planes 103 and 104 disposed on opposite sides of the body 102 are similarly mounted to swing from normal horizontal position into vertical position. For the purpose mentioned the planes 100 and 101 are mounted on shafts 105, 106, and the sustaining planes 103, 104 are mounted on shafts 107, 108, the shafts being journaled in suitable bearings arranged on standards 110 attached to or forming part of the body 102. The shafts 105 and 107 are connected by pulleys 111 and 112 and belts 113 and 114 with pulleys 115 on the shaft 116 journaled on the body 102 and under the control of the pilot, the same as the shaft 46 previously mentioned. The shafts 106 and 108 are similarly connected by pulleys 120, 121 and

crossed belts 122 and 123 with pulleys on the shaft 116 and similar to the pulleys 115. Thus by the pilot turning the shaft 116 the sustaining planes 100, 101, 103 and 104 can be readily swung from their normal horizontal position into vertical position for the purpose above described in reference to the aeroplane shown in Figs. 1 and 2. It is understood that the aeroplane shown in Fig. 3 is provided with the driving propeller 50, the same as above mentioned, so that further description of the action of these two propellers one relative to the other is not deemed necessary.

It will be noticed that the pilot can readily set the sustaining planes into desired angular positions, that is, more or less inclined relative to the extreme horizontal to vertical positions. By setting the sustaining planes into angular positions the resistance of the planes to the air is such that the aeroplane is not liable to take a header, turn turtle, or take a zigzag down course, and the turning of both the safety propeller and the driving propeller prevents a sudden drop of the aeroplane and the pilot is enabled to effect a safe landing in case the motor is damaged and comes to a standstill while the aeroplane is up in the air.

Having thus described our invention, we claim as new and desire to secure by Letters Patent:

1. In an aerial vessel, a motor, a driving propeller, a clutch between the propeller and motor shafts, a safety propeller disposed horizontally and having its axis approximately at the center of gravity of the vessel, a horizontal shaft having one end geared with the safety propeller shaft, a clutch on the horizontal shaft, gearing between members of the said clutches, and means under the control of the operator for alternately throwing the said clutches into and out of engagement.

2. In an aerial vessel, a motor, a driving propeller, a clutch between the propeller and motor shafts, a safety propeller having its axis disposed approximately at the center of gravity of the vessel, a horizontal shaft geared with the safety propeller shaft, a clutch on the horizontal shaft gearing between members of the clutches, a lever pivoted intermediate of its ends and engaging the slidable members of clutches, and means for operating the lever.

3. In an aerial vessel, a motor, a driving propeller, a clutch between the propeller and motor shafts, a safety propeller on a vertical shaft, a shaft geared with the shaft of the safety propeller, a second horizontal shaft having one end geared with the first horizontal shaft, gearing between members of the clutches, a lever pivoted intermediate of its ends and engaging the slidable members of the clutches, an operating lever, and a link

connecting the operating lever with the first named lever.

4. An aerial vessel provided with sustaining planes each formed of two sections, the sections being pivoted at one edge and adapted to swing from normal horizontal position into vertical position, a safety propeller disposed horizontally above the said sustaining planes and having its axis approximately at the center of gravity of the aerial vessel, a motor, a driving propeller driven from the said motor, and a connection under the control of the pilot and adapted to connect the safety propeller with the driving propeller to rotate the latter from the safety propeller in case the motor stops.

5. An aerial vessel provided with upper and lower sustaining planes each formed of two sections, the sections being pivoted at one edge and adapted to swing from normal horizontal position into vertical position, a safety propeller disposed horizontally above the said sustaining planes and having its axis approximately at the center of gravity of the aerial vessel, a motor having a shaft, a driving propeller having a shaft, a clutch connecting the said motor shaft with the said driving propeller shaft, clutch shifting means under the control of the pilot, and a driving connection between the said safety propeller and the said driving propeller to rotate the latter from the safety propeller.

6. An aerial vessel provided with sustaining planes each formed of pivoted sections 35 adapted to swing from normal horizontal position into vertical position, a safety propeller disposed horizontally above the said sustaining planes and having its axis approximately at the center of gravity of the 40 aerial vessel, a motor having a shaft, a driving propeller having a shaft, a clutch connecting the said motor shaft with the said driving propeller shaft, clutch shifting means under the control of the pilot, and a 45 driving connection between the said safety propeller and the said driving propeller to rotate the latter from the safety propeller, the said driving connection having a clutch controlled by the said clutch shifting means. 50

7. An aeroplane provided with sustaining planes each made in two sections, each pivoted at one side of the center to swing from normal horizontal position to vertical position or to any intermediate position, the free 55 inner ends of the sections of a sustaining plane abutting each other when the said plane is in horizontal position.

8. In an aeroplane, sustaining planes each made in two sections, the sections being pivoted adjacent their outer edges to swing toward each other with their free inner ends abutting when in a horizontal position, and means for operating the sections.
